CLAIM

The ornamental design for a bottle carrier, as shown and described.

DESCRIPTION

FIG. 1 is a rear perspective view of a bottle carrier according to our new and ornamental design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a rear perspective view of the second embodiment of a bottle carrier, wherein the front, rear, left side, right side, and top views of the second embodiment of the bottle carrier are identical to those of the first embodiment, respectively; and, FIG. 9 is a bottom view of FIG. 8 thereof.

The broken lines depict portions of the article that form no part of the claimed design.
